UNITED STATES PATENT OFFICE.

EMIL SCHLOSSBERG, OF NEW YORK, N. Y., ASSIGNOR OF ONE-HALF TO THE DECKER COMPANY, OF NEW YORK, N. Y.

COMBINED SPONGE-CUP AND CHALK-HOLDER.

1,151,404.

Specification of Letters Patent. Patented Aug. 24, 1915.

Application filed May 12, 1915. Serial No. 27,544.

To all whom it may concern:

Be it known that I, EMIL SCHLOSSBERG, a subject of the Czar of Russia, and a resident of the city of New York, borough of Brooklyn, in the county of Kings and State of New York, have invented a new and Improved Combined Sponge-Cup and Chalk-Holder, of which the following is a full, clear, and exact description.

10 My invention relates to a combined sponge cup and chalk holder for bowling alleys.

An object of the invention is to provide a simple, convenient and inexpensive sponge and chalk holder combined, in which the

15 holder is detachable from the sponge cup, and which holder forms a retainer for the sponge within the cup whereby the same cannot be detached from the cup unless the holder is removed.

20 A further object of the invention is to provide a chalk holder in which the chalk is firmly secured to the holder.

With the above and other objects in view, the nature of which will more fully appear 25 as the description proceeds, the invention consists in the novel construction, combination and arrangement of parts as herein fully described, illustrated and claimed.

In the accompanying drawings, forming 30 part of the application, similar characters of reference indicate corresponding parts in both views.

Figure 1 is a vertical section of my device; and Fig. 2 is a perspective view of the 35 sponge-cup lining.

Referring to the drawings, 3 represents a cup which has a central projection 4. The cup is lined with metal 5 spun to the configuration of the cup 3. Of course, it is 40 self-evident that, if desired, the cup can be formed entirely of metal or entirely of wood. The metal lining is preferable for the reason that it prevents the warping of the wooden cup. The cup 3 in this case is shown 45 secured to a bowling-alley post 6. Threaded axially in the projection 4 is a stud 7 on to which is threaded a chalk support 8 of the chalk holder 9. The bottom of the support engaging the projection 4 is of a larger 50 diameter than the projection, so that the bottom overhangs the projection and, consequently, retains the sponge 10 within the cup, as clearly indicated. Mounted on the top of the support is a piece of frustocone-shaped chalk 12 having an axial bore. The

support 8 adjacent the top has a cone-shaped portion 13 forming an extension of the cone surface of the chalk 12. A frusto-cone-shaped ring 14 engages the cone surface 13 of the support 8 and also a portion 60 of the cone surface of the chalk member 12 adjacent the support 8. This ring draws the chalk to the support and retains it thereat when the ring is secured to the support by means of screws 15 or any other suitable 65 means. The frictional engagement between the ring 14 and the chalk is such as to prevent the rotation of the chalk within the ring.

From the above description it will be seen 70 that although the sponge 10 presents a large area for the players to wipe their fingers on, the players are prevented from pulling the sponge out of the cup by the provision of the central projection 4 to which is detachably 75 secured the chalk holder 9. The chalk piece 12 presents all the facility necessary for the players to chalk their hands but prevents the players from removing the chalk from the holder; thus, neither the sponge nor the 80 chalk can be mislaid.

While I have described the principle of operation, together with the device which I now consider to be the best embodiment thereof, I desire to have it understood that 85 the device shown is merely illustrative and that such changes may be made as are within the scope of the appended claims.

I claim:

1. A combined sponge and chalk holder 90 for bowling alleys comprising a sponge cup and a chalk holder removable from the cup and forming a retainer for the sponge in the cup so that the same can not be removed unless the holder is detached.

2. A combined sponge and chalk holder for bowling alleys comprising a sponge cup and a chalk holder in the central part of the cup raised above the same and detachably associated therewith, said holder forming a 100 retainer for the sponge so that the same cannot be removed from the cup unless the holder is removed.

3. A combined sponge and chalk holder for bowling alleys comprising a sponge cup having a central projection, a chalk holder detachably secured to the projection, the bottom of the chalk holder engaging the projection being larger than the projection 105 to form a retainer for the sponge in the cup, 110

so that the cup cannot be removed unless the holder is detached.

4. A combined sponge and chalk holder for bowling alleys comprising a sponge cup having a central projection raised to the level of the edge of the cup, an annular sponge within the cup engaging the projection, and a chalk holder detachably secured to the projection, the base of the chalk holder engaging the projection being larger than the projection to engage the sponge within the cup.

5. A sponge cup having a central projection, a lining for the interior of said cup and over the projection, an annular sponge engaging the lining and fitting over the projection, and a detachable chalk holder secured to the projection, the base of the

chalk holder overhanging the projection to engage the sponge, whereby the same is retained within the cup on the lining.

6. A combined sponge and chalk holder for bowling alleys comprising a sponge cup and a detachable chalk holder forming a retainer for the sponge in the cup, said chalk holder comprising a support, a chalk piece on said support, and means detachable from the support for securing the chalk to the support.

In testimony whereof I have signed my name to this specification in the presence of two subscribing witnesses.

EMIL SCHLOSSBERG.
